UNITED STATES PATENT OFFICE.

EDWARD C. CLARK, OF NUTLEY, NEW JERSEY, ASSIGNEE TO THE OSCAR BARNETT FOUNDRY COMPANY, A CORPORATION OF NEW JERSEY.

CHAIN GRATE.

972,751.

Specification of Letters Patent. Patented Oct. 11, 1910.

Application filed February 11, 1910. Serial No. 543,266.

To all whom it may concern:

Be it known that I, EDWARD C. CLARK, a citizen of the United States, residing at Nutley, in the county of Essex and State of New Jersey, have invented certain Improvements in Chain Grates, of which the following is a specification.

This invention relates to means for connecting the bars of a chain grate to the endless conveyer chains, and the objects of the invention are to secure simplicity of construction, and as few parts as possible; to fasten the bars securely to the chains and yet allow free movement of said chains in traveling around their sprocket wheels; to enable the bars to be easily and conveniently removed or detached from the chains when desired, and to obtain other advantages and results as may be brought out in the following description.

Referring to the accompanying drawings, in which like numerals of reference indicate corresponding parts in each of the several figures, Figure 1 is a plan view of a single grate bar mounted upon the opposite chains of a chain grate of my improved construction, only portions of said chains being shown and the grate bar being broken away at its middle; Fig. 2 is a side elevation of the grate bar, showing the chains in vertical cross section directly beneath the grate bar; Fig. 3 is a vertical cross section of the grate bar at the point of its attachment to a flatwise link, said section being on line 3-3 of Fig. 2, and looking in the direction indicated by the arrow; Fig. 4 is a plan of the chain and fastening shoe, at the point of attachment of the grate bar to a flatwise link, the grate bar being removed, and Fig. 5 is a side elevation of the fastening shoe, looking in the direction of the length of the chain.

In said drawings, 10 indicates one of the transverse grate bars of a chain grate, and 15, 25 are sections of the two endless conveyer chains to which the opposite ends of said bars are attached.

16 indicates a vertical or edgewise link of the chain section 15 into which the hooked

end 11 of the grate bar engages, and 26 indicates an opposite horizontal or flatwise link of the chain section 25 to which the other end 12 of the grate bar is secured, this being the common arrangement of the grate bars upon the conveyer chains in a chain grate, as shown in United States Patent No. 852264, for instance, I have shown in the drawings a hook 18 upon the hooked end 11 of the grate bar, which projects toward the extremity of the bar from an enlargement 19 on the under side of the bar, substantially as in said prior patent. It will be understood that this hook 18 is pushed into the loop of the vertical or edgewise link 16 from the inner side of the chain 15 and so clasps the upper strand of the link between itself and the grate bar, as clearly shown in Fig. 2. It is to the means for securing the other end 12 of the grate bar to the chain 25, after the hooked end 11 has been inserted as described, that the present invention more particularly relates.

The grate bar 10 has a bottom rib 18, which at the end 12 of the bar rests upon the upper side of the horizontal-link 26 or link which in passing around the sprocket wheels 75 or the like upon which the conveyer chain is mounted, and which are not shown herein, lies flatwise against the periphery of the same, so that such alternate links are more properly called "flatwise links" than "horizontal links". Said rib has formed in its edge next the chain a socket 27 extending toward and preferably into the body of the grate bar, said socket being shown as rectangular in cross section, although I do not limit myself to that shape. The shank 28 of a shoe 30, having a head 29 at the opposite side of the chain 25 from the grate bar 10, passes up through the flatwise link 26, between the ends of the two adjacent edgewise links 261, 261, and enters the socket, which it fits nicely. A cross piece 31, which I have shown as consisting merely of a piece of stout wire with the ends bent over, is put through registering holes 32, 33, drilled transversely through the grate bar or its rib

13 and the shank 28 of the shoe, to retain said shoe against escape from its socket. It will thus be seen that the grate bar, or its end 12, is securely attached to the chain 25. At the same time, the attachment of said end 12 of the grate bar to the shoe provides for perfect freedom of action of the links of the chain upon one another, and thus does not restrict its bending or interfere in any way with the travel of the chain upon its sprocket wheels or rollers, because of the detail construction next to be described. The head 29 of the shoe 30 provides at opposite sides of the shank 28, or toward the opposite sides of the chain, shoulders 34, 34 for the flatwise link 26 to rest upon, and at each of its other two opposite sides, or sides facing lengthwise of the chain, the shank has checks 35, 35 adapted to fit against the end of the adjacent vertical link 261 and forming a rounded seat therefor. The head 29 is also recessed, as at 36, to form a continuation of said seat for the end of the adjacent vertical link, said recess being suitably curved to fit the link, as shown in Fig. 3. Furthermore, the opposite lower edges of the rib 13 may be recessed as at 37, 37, if necessary or desirable, to receive the upper parts of the vertical links 261 and form curved seats therefor, as shown in Fig. 3 also. These curved seats are in substantial alignment transversely of the grate bar with the socket 27, and the hole 32 for the pin 31 is drilled through the rib 13 between said seats and the body part of the grate bar so as to clear the seats. By my invention, therefore, the end 12 of the grate bar is attached to the conveying chain 25 by simply resting it upon a flatwise link and then passing the fastening shoe 30 through said flatwise link from its side away from the bar, the shank of said shoe entering the socket 27 in the bar, and the cross pin 31 when put in place locks the whole together. There is thus a minimum of parts and of operations, and furthermore the grate bars are held firmly in position on the chains. Especially do the curved seats on the head of the fastening shoe, facing lengthwise of the chains and at the opposite side thereof from the grate bars, serve to prevent any tipping over or tilting of the bars. So also do the curved seats formed directly on the grate bars and engaging the adjacent side of the chains prevent any looseness of each bar with respect to its link, and particularly when in combination with the other curved seats just mentioned.

While the links of the chain must move freely on one another for the usual undulating motion of this class of chain grates, it is also necessary for the same purpose that each bar be rigid enough with respect to its link so that the motion is not lost between

the chain and bars. This result my improved connecting shoe secures to a marked 65 degrees.

Having thus described the invention, what I claim is—

1. The combination with a chain, and a transverse member at one side thereof, of a 70 fastening shoe forming at one end portion of itself a shank which will pass through a link of the chain, said shoe being inserted in a link, means securing the end of said shank to the said transverse member, and a 75 head at the other end of the shoe having in opposite sides of itself curved seats fitting the ends of adjacent links at the opposite side of the chain from the transverse member.

2. The combination with a chain, and a transverse member at one side thereof, of a 80 fastening shoe forming at one end portion of itself a shank which will pass through a link of the chain, said shoe being inserted in a link, means securing the end of said shank to the said transverse member, and a head at the other end of the shoe lying at the opposite side of the chain from the transverse member, said head having at its 85 sides facing lengthwise of the chain seats fitting the ends of adjacent links and at its other sides seats for the parallel portions of the link through which the shoe extends.

3. The combination with a chain, of a 90 transverse member lying across a link of said chain and having at its opposite sides seats for the ends of adjacent links, a fastening shoe forming at one end portion of itself a shank which will pass through a link 100 of the chain, said shoe being inserted in the link across which the transverse member lies, means securing the end of said shank to said transverse member, and a head at the other end of the shoe adapted to engage the 105 opposite side of the chain from the transverse member.

4. The combination with a chain, of a transverse member lying across a link of 110 said chain and having at its opposite sides seats for the ends of adjacent links, a fastening shoe forming at one end portion of itself a shank which will pass through a link of the chain, said shoe being inserted in the link across which the transverse member 115 lies, means securing the end of said shank to said transverse member, and a head at the other end of the shoe having in opposite sides of itself curved seats fitting the ends of adjacent links at the opposite side of the 120 chain from the transverse member.

5. The combination with a chain, of a transverse member lying across a link of 125 said chain, said member having a socket in its face next said link and seats in its opposite sides for the ends of adjacent links, said

socket and seats being substantially in alignment transversely of the member, a fastening shoe forming at one end portion of itself a shank which will pass through a link of the chain and having at its other end a head too large to pass through the link, said shoe being inserted in the chain with its shank extending through said link across which the transverse member lies and into

said socket of the transverse member, and pin passed through said transverse meml and shank at the opposite side of said late seats of the transverse member from the chain.
